UNITED STATES PATENT OFFICE

135,375

DESIGN FOR A HOUSING FOR A FLUORESCENT LIGHTING FIXTURE

David J. Biller, St. Louis, Mo., assignor to Day-Brite Lighting, Inc., St. Louis, Mo., a corporation of Missouri

Application May 28, 1942, Serial No. 107,032

Term of patent 14 years

To all whom it may concern:

Be it known that I, David J. Biller, a citizen of the United States and a resident of the city of St. Louis and State of Missouri, have invented a new, original, and ornamental Design for a Housing for a Fluorescent Lighting Fixture, of which the following is a specification, reference being had to the accompanying drawing, forming part thereof.

Fig. 1 is a perspective view of a housing for a fluorescent lighting fixture, showing my new design; and

Fig. 2 is a view of the opposite end of the housing from that appearing in the perspective view.

I claim:

The ornamental design for a housing for a fluorescent lighting fixture, as shown.

DAVID J. BILLER.
